Primary Examiner — Karen E Kearney(74) *Attorney, Agent, or Firm* — Skaar Ulbrich Macari, P.A.(57) **CLAIM**

We claim the ornamental design for a data accessing device, as shown and described.

DESCRIPTION

FIG. 1 is a perspective view of a data accessing device showing the claimed design;

FIG. 2 is another perspective view of FIG. 1;

FIG. 3 is a front elevational view of FIG. 1;

FIG. 4 is a rear elevational view of FIG. 1;

FIG. 5 is a left side elevational of FIG. 1;

FIG. 6 is a right side elevational of FIG. 1;

FIG. 7 is a top plan view of FIG. 1;

FIG. 8 is a bottom plan view of FIG. 1;

FIG. 9 is a perspective view showing the data accessing device in a usage state; and,

FIG. 10 is another perspective view of FIG. 9.

The broken lines are directed to environment and are provided for illustrative purpose only; the broken lines form no part of the claimed design.
